[57] CLAIM

The ornamental design for a housing for a hinge for a spectacle frame, as shown and described.

DESCRIPTION

FIG. 1 is a top plan view of a housing for a hinge for a spectacle frame showing my new design;

FIG. 2 is a side elevational view thereof;

FIG. 3 is an opposite side elevational view thereof;

FIG. 4 is a bottom plan view thereof;

FIG. 5 is a front elevational view thereof;

FIG. 6 is a rear elevational view thereof;

FIG. 7 is an enlarged front perspective view thereof.

FIG. 1

FIG. 2

FIG. 3

FIG. 4

FIG. 5

FIG. 6

FIG. 7
